O. S. LEE

VICE STAND

Filed Jan. 7, 1927

UNITED STATES PATENT OFFICE.

OTTAR S. LEE, OF CHICAGO, ILLINOIS, ASSIGNOR TO NYE TOOL & MACHINE WORKS, OF CHICAGO, ILLINOIS, A CORPORATION OF ILLINOIS.

VISE STAND.

Application filed January 7, 1927. Serial No. 159,601.

As a preface to the following description of my invention, it may be stated that as vise-stands have hitherto been provided considerable difficulty has been experienced in the tilting or canting of the stands on the floor upon which they rest, when subjected to considerable force by the workman, as for example in the threading of relatively large pipes held in the vise, the resistance presented by the pipe, to the rotation of the cutting die applied thereto, causing the stand to tilt or cant as stated.

My object is to provide simple and economical means, and which may be applied to vise-stands now in use for preventing such tilting or canting action, and without danger of impairing the stand.

Referring to the accompanying drawing:—

Figure 1 is a view in side elevation of a vise-stand equipped with my invention. Figure 2 is a broken sectional view of a portion of the means whereby such tilting or canting of the stand is prevented, the section being taken at the line 2 on Fig. 3 and viewed in the direction of the arrow; and Figure 3, a broken plan view of the portion of the structure shown in Fig. 2 with certain parts omitted.

The particular construction of vise stand illustrated is of common and well-known form, the stand comprising a top portion 10 of frusto-pyramidal form, providing the top plate 11 and the upwardly converging side plates 12 each of which is apertured as represented at 13, and four legs 14 which fit into the corners of the top portion and are rigidly secured thereto, by which arrangement the legs spread outwardly from the top portion 10. The stand thus provided is surmounted by the vise represented at 15, (the vise being shown by an edge view) which extends across the front marginal edge portion of the stand-top 10 and is rigidly secured thereto in any suitable way. The stand-top also carries, in accordance with common practice, a pipe-rest represented at 16 for supporting the end of the pipe which projects rearwardly beyond the vise 15.

In accordance with my invention means are provided which operate as a stop to prevent the tilting or canting of the stand in operating upon an object clamped in the vise 15, these means being provided for interposition between the stand and the ceil-

ing, represented at 17 in the drawings of the room in which the stand is located, the stand, resting on the floor 18 of the room.

The stop means referred to and which engage with the stand preferably at the right-hand side of the latter, viewing the stand from the front thereof, namely, from the left in Fig. 1, comprise, according to the preferred illustrated embodiment of the invention, a vertically-disposed threaded rod 19 which has screw-threaded engagement with the top portion 10 of the stand and is provided at its upper end with a head 20 rigid therewith, and terminating in an upwardly tapering stud-portion 19^a; a pipe member 21 telescoped at its lower end with the stud portion 19^a and interposed between the head 20 and the ceiling 17, and a bearing head 21^a which fits up against the ceiling and telescopes at its depending tapering stud portion 21^b with the upper end of the pipe 21. The rod 19, in applying the stop means to position, is turned at its threaded connection with the stand to a position in which the upper end of the head 21^a is forcibly pressed upwardly against the ceiling 17 thus firmly forcing the stand against the floor and firmly holding it against the canting or tilting action referred to. The head 20 is shown as of hexagonal form and is provided with an opening 22 whereby the rod 19 may be turned, as desired, either with a wrench or by a rod introduced into this opening.

The engagement of the rod 19 with the stand may be at any desirable place thereon, but preferably such engagement, particularly when the stop means are to be used on vise-stands now in use, is at a bracket 23 provided as a part separate from the stand and adapted to be rigidly and firmly secured in position on the latter. The form of bracket shown is particularly adapted for application to a stand of the particular form shown and serves to so distribute the forces exerted against the stand when the stop means are brought into play, that danger of impairment of the stand, even when the parts thereof are relatively thin, is reduced to the minimum, this bracket being formed to provide a relatively heavy outer end portion 24 threaded to receive the rod 19 and a lighter tail portion 25 which overlaps the marginal edge of the plate portion 11, the form of this bracket

being such as shown that its underside presents an angular recess 26 at which it fits conformingly an edge portion of the stand 10 as shown in Fig. 2. Both the stand and the tail portion 25 of the bracket contain openings represented at 28 and 29, respectively, to receive a bolt 30 which rigidly holds the bracket in place on the top portion 10 of the stand.

10 It will be understood from the foregoing that by my invention I provide simple and economical means for preventing tilting or canting of the vise-stand, and of such character that they may be readily released, 15 when it is desired to shift the stand to a new location, and quickly reconditioned for use following the re-positioning of the stand.

20 While I have illustrated and described a particular embodiment of my invention, I do not wish to be understood as intending to limit it thereto as the same may be variously modified and altered without departing from the spirit of my invention.

25 What I claim as new and desire to secure by Letters Patent, is:

1. In combination, a vise-stand having a vise thereon for clamping a pipe to be operated on, and means cooperating with said stand and a fixed structure above it for resisting force applied to the stand and tending to tilt the latter, and comprising a bracket presenting an angular recess at its underside at which it fits over the edge portion of the top of the stand and engages the upper and side surfaces of said top, and stop means interposed between, and engaging said bracket and said fixed structure.

2. In combination, a vise-stand having a vise thereon for clamping a pipe to be operated on, and means cooperating with said stand and a fixed structure above it for resisting force applied to the stand and tending to tilt the latter and comprising a bracket having an angular recess at which it fits over the edge portion of the top of the stand and engages the upper and side surfaces of said top, means for securing said bracket in place on said stand and stop means engaging said bracket and said fixed structure.

OTTAR S. LEE.
